TOOL FOR HYDRAULICALLY DISPLACING
WELL MATERIALS

Wilber A. Maxwell, Houston, Tex., and John A. Engstrand, Los Angeles, Calif., assignors to Grant Oil Tool Company, Los Angeles, Calif., a corporation of California

Application May 5, 1947, Serial No. 746,038

5 Claims. (Cl. 294—86)

1

This invention relates to improved apparatus for the displacement or recovery of solid materials and bodies in oil wells, and having as a general mode of operation such displacement or recovery by the creation of a fluid surge resulting from the opening of a low pressure chamber into communication with the displacement zone.

Heretofore this same type of operation has been extensively employed in the use of suction-type bailers and cleaners in various forms utilizing normally closed chambers lowered within the hydrostatic well fluid column to the bottom of the well or other location at which solids are to be displaced, the chambers having closures adapted to be suddenly opened to admit to the chambers hydraulic material-displacing surges which occur under pressures corresponding to the hydrostatic head of the well liquid column standing above the displacement zone at which the chamber inlet ordinarily is located. In instances where the extent of the hydrostatic column above the displacement is great, the differentials between the hydrostatic and empty charge receiving chamber pressures are correspondingly great, the result being that when the chamber is suddenly opened, the responsive fluid flow or surge into the chamber occurs with considerable violence. Now it has been found that the magnitude and violence of such surges are frequently so great as to create seriously undesirable disturbances in the well, such as the displacement of excessive quantities of sand into the well, collapsing of weak casing or liners, and like effects. Heretofore, such consequences have been unavoidable for the reason that the hydrostatic column-chamber pressure differential and the fluid flow or surge proportionate to that differential have been fixed because the displacement zone and the chamber inlet have been under virtually the same hydrostatic pressure, and the chamber constitutes a closed empty zone under atmospheric pressure.

The primary object of the present invention is to avoid the abovementioned consequences of violent pressure surges in the displacement or recovery of solid materials from a well, by providing for the maintenance of any desired differential between the chamber pressure and the hydrostatic displacement zone pressure, and in so doing to diminish to whatever extent desired the violence of the surge that would ordinarily occur at the displacement zone depth employing the conventional methods and equipment.

More specifically, the invention contemplates lowering in the well a normally closed chamber

2

communicable with the displacement zone but positionable above that zone a distance sufficiently remote therefrom that the effective hydrostatic pressure of the fluid tending to enter the chamber will be less than the hydrostatic pressure on the displacement zone, to a degree such that when the chamber is opened, the consequent liquid in-surge will have no greater activity or violence than that necessary for movement of solids in the displacement zone. As will be apparent, the chamber position may be at any submergence depth in the hydrostatic column, so that the effective column-chamber pressure differential may be selected or predetermined as desired to create sufficient surge for displacement of the solids, while insuring against a surge violence productive of adverse results.

A further object of the invention is to provide for simple incorporation of the charge receiving chamber and its communication with the displacement zone, in a drill pipe string including a lower section extending down to the displacement zone, and an upper section containing the charge receiving chamber and extending to a depth determinative of the chamber inlet fluid pressure and the activity of the surge to be communicated to the displacement zone. As will appear, the pipe string sections are so connected as to have relative movement by virtue of which the charge receiving chamber is opened, and to permit the well fluid to rise to chamber height within the lower section.

Also contemplated is the provision of a tool on the pipe string for receiving and retaining solid materials displaced by the liquid surge. For this purpose I may employ a tool of the so-called "junk basket" type carried by the lower pipe string section and through which the displacement zone is in communication with the charge receiving chamber.

The abovementioned as well as various additional features and objects of the invention will be more fully explained in the following detailed description of the illustrative embodiment shown by the accompanying drawing, in which:

Fig. 1 is a view showing the apparatus in elevation within a well;

Figs. 2 and 3 are enlarged vertical sections taken respectively on lines 2—2 and 3—3 of Fig. 1; and

Fig. 4 is a cross-section on line 4—4 of Fig. 2.

The apparatus comprises a pipe string run into the well bore 10 and including a lower section 11 and a relatively vertically movable upper section 12 extending to the ground surface. As will

appear, the upper section of the pipe string, or at least the lower portion thereof, constitutes a normally closed low pressure chamber communicable with a lower zone at which the displacement of material is to be effected, and so positioned in the well that the effective pressure of the hydrostatic well fluid column tending to enter the chamber upon its opening, may be any amount less than the hydrostatic column pressure at the displacement zone, depending upon the depth at which the chamber opening, i. e. the bottom portion of the pipe string section 12, is positioned in the well. Thus it will be understood that the well bore will contain a hydrostatic column extending above the bottom portion of the pipe string section 12, and that the length of the latter may be varied as desired, to give any predetermined or selected pressure differential inside and outside the low pressure chamber 13 when the latter is opened. The displacement zone 14 is shown to be at the bottom of the well, and may be assumed to contain displaceable solids of any character, and particularly metallic or other objects retrieveable in a so-called "junk basket" type of fishing tool, for removal to the ground surface.

The pipe string sections 11 and 12 are shown to be interconnected by a telescopic joint assembly generally indicated at 15, and including a closure for the bottom of the chamber 13, and means operable by relative vertical movements of the sections to open the closure. Referring to Fig. 2, section 12 is connected by tubular coupling 16 and the threaded joint at 17 with a sleeve 18, the latter having a counterbore 19 forming an annular shoulder 20. In the broad contemplation of the invention, the chamber 13 may have any suitable type of bottom closure 21 capable of being opened by manipulation of the pipe string to admit well fluid to the chamber. As illustrative, the closure is shown to consist of a frangible disc 22 confined between gaskets 23 by a bushing 24 screwed into the lower threaded end of the coupling 16, the bushing having a frustro-conical surface 25.

Sleeve 18 is connected with the top coupling end 26 of the lower pipe string section 11 by a tubular mandrel 27 threaded at 28 into the coupling and having splines 29 extending through ways 30 in the sleeve, see Fig. 4, the splines permitting transmission of rotation from the upper to the lower string section as for turning the fishing tool into the bottom sand. The mandrel 27 has an enlarged diameter disc breaker head 31 engageable against shoulder 20 to suspend the string section below, and containing one or more lateral openings 32 through which fluid may pass upwardly from section 11 into the space 33. Head 31 may carry the O type seal rings 311 to prevent fluid leakage along the head. Upon downward movement of the upper section 12 relative to the lower section 11, the disc 22 is fractured by impact against the pointed breaker head 31a, relative movement of the breaker toward the disc being limited by engagement of the lower end of the coupling 18 with tool joint 26. Full opening of the chamber inlet may be effected by raising the seat 25 from the breaker after the disc is ruptured. In order to assure quick and complete rupturing of the disc, impacting of the latter against the breaker may be caused to occur under substantial load from above, as by using a shear pin 35 projecting into and engageable with the end of the mandrel recess 36 until the superposed load is sufficiently

great to shear the pin, at which point the disc is suddenly dropped against the breaker.

The lower string section 11 may carry any suitable form of tool adapted to receive and retain solids displaced from the zone 14, as a result of an upward fluid surge created by opening the chamber 13. Typically the tool 136 is shown to comprise a tubular body 37 connected by coupling 38 to the pipe string and having a bottom coring edge 39 capable of penetrating the sand in the bottom of the well. The body may contain one or more sets of retainers, such as the circular arrangement of radially deflectable fingers 40 shown in Fig. 3, past which the solids are carried upwardly by the fluid surge to thereafter be retained by the finger assembly.

Suitable provision may be made for venting gas or air from the top of the lower pipe string section 11 as the latter is run down through the hydrostatic column, as by means of a valvular gas release preventing in-flow to the string when the low pressure chamber is opened. Referring to Fig. 2, coupling 26 may contain a pressure release, generally indicated at 40 comprising a ball valve 41 contained in bore 42 and seating against shoulder 43 to control the gas escape from the string section 11 through passages 44 and 45. Opening of the valve is resisted by coil spring 46, the compressive force of which is adjustable by plug 47 to maintain any desired seating thrust against the valve. As illustrative, the pressure release may be set to permit opening of the valve at a gas pressure of around 100 lbs. per sq. in.

In operation the apparatus is run into the well in the condition illustrated in Figs. 1 and 2 with the connection 15 located at a remote elevation above the displacement zone 14. As illustrative, depending upon the desired pressure differential conditions, the low pressure chamber inlet 48 may be located in excess of 500 to 1000 feet above the displacement zone. As the equipment is lowered down through the hydrostatic column of well fluid, the latter may be permitted to rise within the lower string section 11 to the height of the disc 22 (when the latter is lowered below the top of the hydrostatic column) because of the capacity of the pressure release 40 to open and vent gas or air from the lower string section. Assuming the tool 136 to be bottomed in the sand, downward movement of the upper string section 12 causes the disc to be impacted and ruptured against the breaker head, as described, whereupon the chamber 13 is opened to admit a high velocity surge of well fluid from the displacement zone 14 upwardly through the lower string section. As will be understood, however, the effective pressure differential under which the fluid enters the chamber, is the difference between the normal internal pressure of the chamber and the hydrostatic pressure of the well fluid column standing above the chamber inlet. Thus, though directly communicated to the displacement zone 14, the action or magnitude of the surge will be far less than that which ordinarily results from the opening of a chamber at the depth of the displacement zone and with consequent excessive disturbances in the well.

We claim:

1. Apparatus for displacing material at a location in a well containing a hydrostatic column, that includes a vertically extending continuous tubular pipe string lowered in the well to said location and comprising upper and lower sections, said lower section communicating with the well

liquid at said location and containing a body of liquid extending upwardly high above said location, a closure in the pipe string at a remote position above said location and initially closing a lower inlet end of said upper section against entry of the well liquid from said lower section, said inlet when opened being communicable with said location through said lower section of the pipe string, the pressure of the column liquid tending to enter said upper section being reduced by said liquid in the lower section to a value exceeding the pressure inside the upper section by an amount substantially less than the hydrostatic column pressure at the depth of said location, said pipe string including a joint interconnecting said sections for relative vertical movement, a member movable relative to one of said sections in response to relative vertical movement of the sections, said member being positioned to upon said movement act against and open said closure to thereby create a surge of liquid upwardly through said lower section from said location, said lower section comprising a large number of pipe stands connected in an end to end series and extending downwardly beneath the upper section inlet and beneath said last mentioned member toward said location, and a tool carried at said location by a bottom one of said stands for receiving well material displaced by the surge.

2. Apparatus as recited in claim 1, in which said pipe string contains a vent opening placing an upper portion of said lower section in communication with the well at the outside of the pipe string to vent gas from the lower section and thereby cause the lower section to fill with well liquid to substantially the height of the upper section.

3. Apparatus as recited in claim 2, including a check valve preventing fluid inflow through said vent opening and into said lower section of the pipe string.

4. Apparatus for displacing material at a location in a well containing a hydrostatic column, that includes a vertically extending continuous tubular pipe string lowered in the well to said location and comprising upper and lower sections, said lower section communicating with the well liquid at said location and containing a body of liquid extending upwardly high above said location, a closure in the pipe string at a remote position above said location and initially closing a lower inlet end of said upper section against entry of the well liquid from said lower section, said inlet when opened being communicable with said location through said lower section of the pipe string, the pressure of the column liquid tending to enter said upper section being reduced by said liquid in the lower section to a value exceeding the pressure inside the upper section by an amount substantially less than the hydrostatic column pressure at the depth of said location,

said pipe string including a joint interconnecting said sections for relative vertical movement, said closure being frangible and carried by one of said sections, and a breaker carried by the other section and acting to engage and break the frangible closure upon relative vertical movement of the sections, said lower section comprising a large number of pipe stands connected in an end to end series and extending downwardly beneath the upper section inlet and beneath said breaker toward said location, and a tool carried at said location by a bottom one of said stands for receiving well material displaced by the surge.

5. Apparatus for displacing material at a location in a well containing a hydrostatic column, that includes a vertically extending continuous tubular pipe string lowered in the well to said location and comprising upper and lower sections, said lower section communicating with the well liquid at said location and containing a body of liquid extending upwardly high above said location, a frangible disc seating upwardly within the lower portion of said upper section at a remote position above said location and initially closing a lower inlet end of said upper section against entry of the well liquid from said lower section, said inlet when opened being communicable with said location through said lower section of the pipe string, the pressure of the column liquid tending to enter said upper section being reduced by said liquid in the lower section to a value exceeding the pressure inside the upper section by an amount substantially less than the hydrostatic column pressure at the depth of said location, said apparatus including a joint interconnecting the sections for relative vertical movement, and a breaker carried by the lower section and acting to engage and break the disc upon downward relative movement of the upper section, to thereby create a surge of liquid upwardly through said lower section from said location, said lower section comprising a large number of pipe stands connected in an end to end series and extending downwardly beneath the upper section inlet and beneath said breaker toward said location, and a tool carried at said location by a bottom one of said stands for receiving well material displaced by the surge.
